(57) **CLAIM**

The ornamental design for a mating section of male electrical connector, as shown and described.

DESCRIPTION

FIG. 1 is a top, front, left side perspective view of my new design of a mating section of male electrical connector.

FIG. 2 is a front side elevational view thereof.

FIG. 3 is a top plan view thereof.

FIG. 4 is a bottom plan view thereof.

FIG. 5 is a left side elevational view thereof.

FIG. 6 is a right side elevational view thereof; and, FIG. 7 is a rear side elevational view thereof.

The broken lines in FIGS. 1, 2, 3 and 7 represent environment only, and form no part of the claimed design. The unshaded circular surface in the central part of FIG. 7 forms no part of the claimed design.
